UNITED STATES PATENT OFFICE.

SAMUEL SWEENEY, OF WILKINSBURG, PENNSYLVANIA.

PIPE-JOINT.

1,365,805.

Specification of Letters Patent. Patented Jan. 18, 1921.

Application filed February 28, 1919. Serial No. 279,820.

To all whom it may concern:

Be it known that I, SAMUEL SWEENEY, a subject of the King of England, residing at Wilkinsburg, in the county of Allegheny and State of Pennsylvania, have invented certain new and useful Improvements in Pipe-Joints, of which the following is a specification.

This invention relates to pipe-joints and joint-mold therefor, and has for one of its objects to provide, in a manner as herein-after referred to, a pipe joint whereby the molten metal cast around the pipe sections will be prevented from burning through the ends of the overlapping pipe sections under such conditions overcoming leakage when the joint is formed.

A further object of the invention, is to provide, in a manner as hereinafter referred to, a joint mold which may be quickly and nicely fitted around the pipe sections to be joined, and which will enable molten metal to be cast at the joint in a uniform manner giving the joint a neat appearance when completed.

A further object of the invention is to provide in a manner as hereinafter set forth, means for joining pipes of the same or different diameters, and refers more especially to such joints known as "wiped" joints, whereby the ends of pipes of different metals may be joined, such as lead and brass, and when joined providing a neat or uniform joint and overcoming leakage due to the burning through of the pipe sections, at their ends, caused by the molten metal when cast to form the joint.

With the foregoing and other objects in view the invention resides in the novel combination, construction and arrangement of parts as hereinafter referred to and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1, is a longitudinal sectional view of the joint and joint mold.

Fig. 2, is a section on line II—II Fig. 1.

Fig. 3, is a view similar to Fig. 1 of a modified form of joint.

Referring to the drawings in detail 1 and

2 denote a pair of pipe sections, the former overlapping the latter, and arranged therein, at the joint ends of the pipe sections, 1, 2, is a sleeve 3, of metallic material different from that of which the pipe sections are formed, and also different from the character of the molten metal 4, which is cast around the pipe sections 1, 2 to close the joint. Preferably when the pipe sections 1, 2 are formed of lead, the sleeve 3, is of brass.

The sleeve 3 is welded to the pipe sections 1, 2 by the heat from the molten metal 4 which is cast around said pipe sections, and in case the metal 4 burns through either of the pipe sections 1, 2 the sleeve 3 being welded against the pipe sections will act as a means to seal the opening formed in the pipe sections by the metal 4.

The pipe sections 1, 2 may be tinned, if desired, prior to the casting of the metal 4 around them. The sleeve 3 is of a length equal to the length of the cast around the pipe sections.

In the modified form shown in Fig. 3, the sleeve is indicated at 5, and is mounted on the periphery of the pipe sections 6, 7, and which is slightly less in length than the length of the cast 8. The sleeve 5 will prevent the burning through of the pipe sections and is welded thereto by the heat from the molten metal which is employed to form the cast 8.

The joint mold, which is employed in forming either form of joint, is formed of two sections each comprising a hollow semi-elliptical body portion 9, terminating at each end in a semi-cylindrical extension, which are indicated at 10, 11. The upper portion of the body 9, at the edge thereof is grooved as at 12, 13, the former being larger than the latter. The extension 10 is formed with a handle member 14.

One of the bodies 9, has a lateral lug 15, which is apertured, and the other of the bodies 9, has a pair of apertured lateral spaced lugs 16, between which extends the lug 15. The lugs 15 and 16 are connected together by a pin 17, whereby the two sections of the joint mold are hinged together.

The extensions 10, 11 when the mold is mounted on the pipe sections form sectional collars, which in connection with the clamping screws 18, maintain the mold in position on the pipe sections.

When the sections of the mold are mounted on the pipe sections and clamped in posi-

tion, the groove 12 of one section registers with the groove 12 of the other section and forms a pouring opening for the molten metal which is to be cast around the pipe sections.

When the sections of the mold are clamped on the pipe sections the groove 13 of one mold section registers with the groove 13 of the other mold section and a vent opening is provided for air, gas or vapor.

Suitable means may be employed for connecting the handle members 14 together to clamp the mold sections in position on the pipe sections.

15 What I claim is:—

1. A pipe-joint comprising the combination with the ends of a pair of pipe sections,

of a body of metal cast around said ends, and a metallic sleeve engaging said ends and welded therewith by the heat from said cast metal body, the sleeve being of a metal different from that of which the pipe sections and cast metal body is formed.

2. A pipe joint comprising the combination with the overlapping ends of a pair of pipe sections, of a metallic sleeve arranged within said sections at said overlapping ends, and a body of metal cast around said overlapping ends to close the joint, said body of a different metal from that of which the sleeve is formed and said sleeve welded to said sections by the heat from said body.

In testimony whereof I affix my signature.

SAMUEL SWEENEY.
